DESIGN FOR A LAPEL BUTTON OR THE LIKE

Samuel Gholson, Cincinnati, Ohio

Application April 6, 1943, Serial No. 109,916

Term of patent 7 years

To all whom it may concern:

Be it known that I, Samuel Gholson, a citizen of the United States of America and a resident of Cincinnati, in the county of Hamilton and State of Ohio, have invented a new, original, and ornamental Design for a Lapel Button or the like, of which the following is a specification, reference being made to the accompanying drawing, forming a part thereof.

Fig. 1 is a top plan view of my design for a lapel button.

Fig. 2 is a side elevational view of my lapel button illustrated in Fig. 1.

I claim:

The ornamental design for a lapel button or the like, as shown.

SAMUEL GHOLSON.
